UNITED STATES PATENT OFFICE.

GREGORY C. DAVISON, OF NEW LONDON, CONNECTICUT, ASSIGNOR TO ELECTRIC BOAT COMPANY, OF NEW YORK, N. Y., A CORPORATION OF NEW JERSEY.

FOUNDATION CONSTRUCTION FOR RECIPROCATING ENGINES.

1,284,255.

Specification of Letters Patent. Patented Nov. 12, 1918.

Application filed April 13, 1916. Serial No. 90,963.

To all whom it may concern:

Be it known that I, GREGORY C. DAVISON, a citizen of the United States, and a resident of New London, in the county of New London and State of Connecticut, have invented certain new and useful Improvements in Foundation Constructions for Reciprocating Engines; and I do hereby declare the following to be a full, clear, and exact description of the invention, such as will enable others skilled in the art to which it appertains to make and use the same.

This invention relates to internal combustion engines and is directed to the provision of an improved construction for the foundation or framing of such an engine upon which the cylinders and other parts are secured with the required high degree of strength and rigidity and which supports and guides certain of the moving parts.

The primary object of the invention is to provide such a foundation construction which is strong and rigid, which is also of light weight and sufficiently open to give access to the interior parts, such as the crank-shaft and cross-head bearings, and with which these ends are secured without an objectionable increase in the length and breadth of the engine.

While the features of the invention are applicable to internal combustion engines of various types and for various purposes, they are of special utility in engines of the heavy oil type employed upon submarine boats.

For such use it is common to employ two of the engines arranged side by side and extending fore and aft of the boat and the space available for the engines is greatly restricted, particularly as to its width. For this reason it is highly desirable that the width of the engine framing be reduced to a minimum and particularly that the supports by which the cylinders are mounted upon the bed-plate of the engine should be

so constructed as not to increase either the length or the breadth of the engine beyond what is made necessary by other considerations. In the engines of this type as heretofore constructed, it has been common to provide pillars or columns erected upon the bed-plate and supporting the cylinders at their upper ends: but in all of these constructions, so far as I am aware, the shape of the columns, particularly at their lower ends, has

been such as to effect an undesirable increase

in the width of the engine in removing the columns from the paths of movement of the cranks and connecting rods, or in the length of the engine in providing space for the columns between adjacent cylinder units.

The present invention involves particularly the provision of a novel form of supporting means by which the cylinders are mounted upon the bed-plate of the engine. This supporting means includes a plurality of transverse frames, preferably of cast steel and of a web and rib construction, these being mounted upon the bed-plate transverse to the length thereof and having the cylinders mounted above their upper ends, the center of each cylinder lying over the space between a pair of adjacent transverse frames. The bed-plate of the engine is provided with webs for the support of the bearings of the crank shaft and each of the transverse frames is mounted upon the bed-plate directly over one of these bearings with its ends secured to the bed-plate on opposite sides of the crank shaft. The cylinders are mounted upon the upper ends of the frames, a sole-plate being preferably provided mounted directly upon the transverse frames and having the cylinders secured thereon.

With this construction a number of advantages of considerable value and importance are secured. The engine structure is strong and rigid and well able to withstand both the sidewise thrust of the cross-heads and racking strains which may result from rolling of the boat. At the same time the structure is of relatively light weight and is sufficiently open to give ready access to the interior parts, such for instance, as the connecting rod bearings. Moreover, no increase in the width or in the length of the engine need be made for the accommodation of the transverse frames, each of which directly overlies one of the crank-shaft bearings and occupies space which would not otherwise be employed. In addition to these characteristics of this foundation construction, the transverse frames may be conveniently utilized as guides for the cross-heads. Preferably each cross-head is provided with a pair of detachable slippers at each end of the cross-head and these slippers may be arranged to travel upon removable guides secured to the transverse frames or upon the frames themselves.

These and other features of the inven-

tion will be better understood by reference to the following description taken in connection with the accompanying drawings, which show the preferred embodiment of the invention. In these drawings, Figure 1 is a side elevation of an engine constructed in accordance with the invention; Fig. 2 is a sectional elevation on line 2—2 of Fig. 1; Fig. 3 is a horizontal section on line 3—3 of Fig. 1; Fig. 4 is a longitudinal section through the bed-plate and transverse frames as indicated by the line 4—4 of Fig. 2; Figs. 5 and 6 are sectional detail views on the lines 5—5 and 6—6 respectively of Fig. 2; Fig. 7 is a perspective view of one of the forms of transverse frames or spacing members utilized in the foundation construction of the engine.

Referring to these drawings, the bed-plate 20 or crank-case A of the engine extends the entire length of the engine and has cross-girders A' for carrying the main bearings, as shown at α in Fig. 4 and at α and α' in Fig. 2 (the last reference letter indicating 25 a separable bearing cap). The cross-girders A' are substantially U-shaped, as is shown in Fig. 2. The end faces of the upstanding legs of the U of each cross-girder are horizontally faced off so that 30 transverse frame members similar to that illustrated in Fig. 7 may be positioned upon each of these cross-girders and be secured thereto so as to be supported thereby. The crank-shaft C is shown in cross section in 35 Fig. 2 and a plurality of cranks thereon are indicated at C' in Fig. 3.

Referring to Fig. 1, the reference S' indicates an intermediate transverse frame or spacing member shown in perspective in 40 Fig. 7 and the reference S'' indicates forward and after transverse frames or spacing members similar to each other but of a shape slightly different from that shown in Fig. 7. The difference in shape between 45 the intermediate and end transverse frames will be apparent on comparison of Figs. 4 and 7. The number of intermediate transverse frames S' will depend upon the number of cylinders employed in the engine, the 50 number of such intermediate transverse frames being always one less than the number of cylinders. In the present instance an engine of two cylinders is illustrated for convenience so that there is shown but a 55 single intermediate transverse frame S' and two end transverse frames S''.

As shown in Fig. 1, a sole-plate P is mounted upon the upper ends of the transverse frames S' and S'' and the cylinders 60 L are mounted upon the sole-plate, the valves of the several cylinders being actuated by a valve gear V.

Referring particularly to Fig. 7, it will be noted that the transverse frame or spacing member S' includes opposite enlarged

leg portions each consisting of side walls 8 and 8', top and bottom walls 9 and a plurality of integral webs and ribs 11. The top walls 9 of the two enlarged end portions are joined by an intermediate web 12 70 and integrally connecting the top walls 9, web 12, and the side walls 8' is a web 13 having the shape of a figure 8. The transverse spacing member constructed in accordance with Fig. 7 is mounted upon the 75 bed plate of the engine over the intermediate transverse web A' and the somewhat similar transverse frames S'' are similarly mounted upon the bed-plate over the transverse webs A' at the ends of the bed-plate. 80

These transverse frames form the support for the sole-plate P upon which the cylinders L are mounted. Each cylinder is provided with a piston whose piston rod is connected to a cross-head H, and each cross-head is connected by a connecting rod to a crank C' on the shaft C. It will be noted, particularly by reference to Fig. 1, that each cylinder is mounted over the space between two adjacent transverse frames and that the 90 cross-heads H reciprocate in the spaces between adjacent transverse frames. These frames are therefore utilized to guide the cross-heads in their reciprocatory movements. For this purpose the portions 10 95 of the side walls 8' of the enlarged end portions of the transverse frames are faced off either to serve as guides for the cross-heads or to receive detachable guides which may be secured thereto. The latter construction is indicated in the drawings 100 wherein the detachable guides are shown at 14, these being secured to the faces 10 of the side walls 8' of the transverse frames. Each cross-head H is provided with a pair 105 of detachable slippers 15 at each end of the cross-head, each pair of slippers being adapted to travel upon the guides 14 mounted upon the adjacent pair of transverse frames. Thus, each cross-head is provided 110 with four slippers and coating guides, two at each end of the cross-head, and each intermediate transverse frame has guides for four slippers thereon, while each end transverse frame has guides for two slippers 115 thereon.

By the employment of the construction herein illustrated and described, great strength and rigidity are obtained both in the lateral and in the longitudinal direction. 120 Such strength and rigidity are due largely to making the transverse frames of cast steel and of a rib and web construction and to splaying out the upper and lower ends of the frames where they are secured to the bed-plate and the sole-plate. Also, by reference to Fig. 1, it will be seen that the structure provides for ready access to such parts as the connecting rod bearings and cross-head bearings, since the casing is open on both 125 130

sides between the transverse frames. Furthermore, it will be noted, particularly by reference to Fig. 2, that this frame construction does not require an increase in the 5 width of the engine beyond that which is required by other considerations. The width of the foundation structure may be the same as or less than the width of the cylinders and their adjuncts, particularly as the transverse 10 frames are mounted under the spaces between adjacent cylinders and over the webs of the bed-plate which carry the crank-shaft bearings and are therefore located between the cranks on the crank-shaft. Furthermore, 15 these transverse frames constructed and positioned, as above described do not necessitate an increase in the length of the engine as they coöperate with the bed-plate and sole-plate in space which otherwise would 20 not be utilized.

I claim:

1. In a multi-cylinder engine, the combination of a bed plate; vertical end and intermediate transverse frames mounted thereon 25 in spaced, parallel relation and comprising, each, a pair of opposite leg portions which straddle the crank shaft of the engine and are integrally connected together, the leg portions of each end frame being provided 30 at the inner side of the frame with a pair of vertical guides disposed at opposite sides of said shaft and in spaced, parallel planes longitudinal of said bed plate, and the leg portions of each intermediate frame having 35 pairs of similarly-disposed guides at both sides of the frame which are arranged opposite and in co-planar relation to the guides on the next adjacent frames; a cross-head movable up and down in the space between 40 each pair of adjacent frames and having co-acting engagement with the guides thereon to be guided by the same; a plurality of cylinders mounted upon said frames and disposed over the cross-heads, each cylinder 45 having its piston connected with the adjacent cross-head; and a connection between each cross-head and the crank shaft.

2. In a multi-cylinder engine, the combination of a bed plate; vertical end and intermediate transverse frames mounted thereon 50 in spaced, parallel relation and comprising, each, a pair of opposite leg portions which straddle the crank shaft of the engine and are integrally connected together, the leg portions of each end frame being provided 55 at the inner side of the frame with a pair of vertical guides disposed at opposite sides of said shaft, and the leg portions of each intermediate frame having pairs of 60 similarly-disposed guides at both sides of the frame which are arranged opposite to the guides on the next adjacent frames; a cross-head movable up and down in the space between each pair of adjacent frames and having 65 co-acting engagement with the guides

thereon to be guided by the same; a plurality of cylinders mounted upon said frames and disposed over the cross-heads, each cylinder having its piston connected with the adjacent cross-head; and a connection between each cross-head and the crank shaft. 70

3. In a multi-cylinder engine, the combination of a bed-plate; a plurality of vertical frames mounted transversely thereon in spaced, parallel relation and comprising, 75 each, a pair of opposite leg portions which straddle the crank shaft of the engine and are integrally connected together, the leg portions of each frame being provided on at least one side of the frame with a pair of vertical guides disposed at opposite sides of said shaft and projecting laterally outward from the side of the frame toward the guides on the next adjacent frame; a cross-head movable up and down in the space between 80 each pair of adjacent frames and having co-acting engagement with the guides thereon to be guided by the same; a plurality of cylinders mounted upon said frames and disposed over the cross-heads, each cylinder having its piston connected with the adjacent cross-head; and a connection, 85 between each cross-head and the crank shaft. 90

4. In a multi-cylinder engine, the combination of a bed plate; a plurality of vertical frames mounted transversely thereon in spaced, parallel relation and comprising, 95 each, a pair of opposite leg portions which straddle the crank shaft of the engine, and are integrally connected together, the leg portions of each frame being provided on at least one side of the frame with a pair of vertical guides disposed at opposite sides of said shaft and projecting laterally outward from the side of the frame toward the 100 guides on the next adjacent frame; a cross-head movable up and down in the space between each pair of adjacent frames and provided at each end with a pair of slippers 105 to directly engage the guides on said frames; a plurality of cylinders mounted upon said frames and disposed over the cross-heads, each cylinder having its piston connected with the adjacent cross-head; and a connection between each cross-head and the crank 110 shaft. 115

5. In an internal combustion engine, the combination of a crank shaft, two cylinders arranged in line over the crank shaft, supporting means for the cylinders including 120 a first frame, a second frame, and a third frame, the frames being spaced along the length of the crank shaft and one of the cylinders being arranged substantially midway between the first and second frames 125 and the other cylinder being arranged substantially midway between the second and third frames, a cross-head below the first cylinder, guiding means for one end of the cross head carried by the first frame, guid- 130

ing means for the other end of the cross-head carried by the second frame, a cross-head below the second cylinder, guiding means for one end of the last mentioned 5 cross-head carried by the second frame, guiding means for the other end of said cross-head carried by the third frame, and operative connections between the pistons in the cylinders, the cross-heads and the crank 10 shaft; substantially as described.

6. In a foundation construction of the kind described, a combined transverse frame and cross-head guiding structure comprising a pair of spaced walls arranged lengthwise 15 with the engine and a joining wall arranged transverse to the engine, the three walls forming a structure H-shaped in horizontal section with the joining wall constituting the cross bar of the H, and four 20 cross-head guides, one mounted on the inner side of each of the two first mentioned walls on each side of the joining wall; substantially as described.

7. In a foundation of the kind described, 25 a unitary cast member having a pair of spaced substantially vertical columns and a central web joining said columns, the plane of the web including the center lines of the columns, and a pair of cross-head guides 30 mounted on each of the columns with the

web between the two guides of each pair; substantially as described.

8. In a foundation of the character specified, a unitary cast member comprising a pair of spaced, substantially-vertical columns and a connecting web between them, each column embodying top and bottom walls and spaced inner and outer side walls, and connecting ribs between said inner and outer side walls, the said inner side walls 40 of said columns having opposite guides disposed longitudinally thereof for engagement by a cross-head.

9. In a foundation of the character specified, a pair of unitary cast supporting members arranged opposite each other in spaced parallel relation and comprising, each, a pair of spaced, substantially-vertical columns and a connecting web between them, each column embodying connected top and bottom walls and inner and outer side walls, and connecting ribs between said inner and outer side walls; the confronting inner faces of said supporting members being provided with longitudinal guides for engagement 45 by the opposite ends of a cross-head movable up and down in the space between said members.

In testimony whereof I affix my signature.
GREGORY C. DAVISON.
